(57) **CLAIM**

The ornamental design for a combined fragrance bottle and cap, substantially as shown and described.

DESCRIPTION

FIG. 1 is a top, left side and front perspective view of a first embodiment of our new design for a combined fragrance bottle and cap;

FIG. 2 is a front elevational view of the combined fragrance bottle and cap shown in FIG. 1; the rear elevational view identical thereto;

FIG. 3 is a left side elevational view of the combined fragrance bottle and cap shown in FIG. 1;

FIG. 4 is a right side elevational view of the combined fragrance bottle and cap shown in FIG. 1;

FIG. 5 is a top plan view of the combined fragrance bottle and cap shown in FIG. 1;

FIG. 6 is a bottom plan view of the combined fragrance bottle and cap shown in FIG. 1;

FIG. 7 is a top, left side and front perspective view of a second embodiment of our new design for a combined fragrance bottle and cap;

FIG. 8 is a front elevational view of the combined fragrance bottle and cap shown in FIG. 7; the rear elevational view identical thereto;

FIG. 9 is a left side elevational view of the combined fragrance bottle and cap shown in FIG. 7;

FIG. 10 is a right side elevational view of the combined fragrance bottle and cap shown in FIG. 7;

FIG. 11 is a top plan view of the combined fragrance bottle and cap shown in FIG. 7; and,

FIG. 12 is a bottom plan view of the combined fragrance bottle and cap shown in FIG. 7.

The broken lines and the area within the broken lines shown in FIGS. 6 and 12 form no part of the claimed design.

1 Claim, 4 Drawing Sheets
